UNITED STATES PATENT OFFICE.

HARRY H. LANDIS, OF TELFORD, PENNSYLVANIA.

HORSESHOE.

1,191,322.

Specification of Letters Patent. Patented July 18, 1916.

Application filed May 10, 1916. Serial No. 96,666.

To all whom it may concern:

Be it known that I, HARRY H. LANDIS, a citizen of the United States, residing at Telford, in the county of Bucks and State of Pennsylvania, have invented a new and useful Horseshoe, of which the following is a specification.

This invention relates to calk attachments for horse shoes, one of its objects being to 10 provide a simple and efficient device which can be applied readily to shoes of different sizes, the said attachment being cheap to manufacture and being formed of but few parts.

15 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

20 In the accompanying drawings the preferred form of the invention has been shown.

In said drawings: Figure 1 is a bottom plan view of a horse shoe having the present improvements combined therewith. Fig. 30 2 is a section on line A—B Fig. 1. Fig. 3 is a section on line C—D Fig. 1. Fig. 4 is a top plan view of the pivot end portion of the calk attachment, the head of the coupling bolt being removed.

25 Referring to the figures by characters of reference 1 and 2 designate opposed arcuate members inturned at one end as indicated at 3 and 4 respectively, these inturned portions lapping. The uppermost one of the inturned end portions, 4, has a short slot 5 therein provided at each end with a substantially circular enlargement 6. Secured within the other inturned portion 3, is a 40 pivot stud 7 having a head which laps the top face of the inturned portion 4, this stud being held against rotation within the member 3 and that portion thereof within the member 4 being flattened as shown at 8. The 45 thickness of the flattened portion of the stud is slightly less than the width of the slot 5 and the diameter of the stud and, consequently, the greatest diameter of the flat portion 8, is slightly less than the diameter

5 of each of the enlarged portions 6. The stud 7 is so positioned that when the members 1 and 2 are oppositely disposed as shown in Fig. 1, the flattened portion 8 of the stud will extend diametrically within one of the enlarged portions 6 so as to be incapable of 60 entering the slot 5. However, by swinging one of the members 1 or 2 relative to the other member, the slot 5 can be brought into line with the flat faces of the portion 8 so that said portion can be slid through the slot 65 5 into the other portion 6 of the slot. Thus the width of the calk attachment can be increased or diminished as desired.

Extending inwardly from the other ends of the members 1 and 2 are arms 9 having inwardly extending eyes 10 in which is mounted a tightening screw 11, this screw engaging the wall of one of the eyes so that when the screw is turned in one direction it will draw the eyes toward each other. Calks 70 12 are secured in any desired manner to the members 1 and 2, these calks being preferably detachably connected thereto. Extending upwardly from each of the members 1 and 2 near the ends thereof are ears 13 and the inner faces of these ears are preferably abraded as shown at 14 so that when the ears engage the sides of a shoe S, they will bite thereinto and be held against displacement. Furthermore the ears are so shaped as to 75 overhang the shoe and therefore further prevent detachment. Likewise, if desired, certain of the ears may be provided with small inwardly directed fingers 15 designed to overhang adjacent portions of the shoe and 80 to wedge between the shoe and the hoof of the animal.

85 It is to be understood that in applying the calk attachment the screw 11 is loosened or removed and the members 1 and 2 are then 90 placed under the shoe so that the ears 14 will engage the outer edges of the sides of the shoe. If the shoe is a large one, the two members 1 and 2 can be adjusted relative to each other by shifting the location of the 95 stud 7 in the manner hereinbefore pointed out. Thus it will be seen that the device can be used with shoes of a number of sizes. After the attachment has been applied to the shoe it can be tightened by means of the 100 screw 11 and accidental detachment thereof is thus prevented.

105 The entire device is light, simple and du-

rable and is particularly advantageous because of its adjustability and the ease with which it can be applied and removed.

What is claimed is:—

- 5 A calk attachment for horse shoes, including opposed bowed members having inwardly extending lapping portions, a stud projecting from one of said portions, there being a stud receiving slot in the other one
- 10 of said lapping portions, said slot having enlargements at its ends, the stud being flattened, the greatest diameter of the flattened portion of the stud being substantially equal

to the diameters of the enlarged end portions of the slot and the smallest diameter of the flattened portion being substantially equal to the width of the intermediate portion of the slot, and means for adjustably connecting the other ends of the members.

In testimony that I claim the foregoing 20 as my own, I have hereto affixed my signature in the presence of two witnesses.

HARRY H. LANDIS.
